UNITED STATES PATENT OFFICE

ARTHUR BATES, OF LEICESTER, ENGLAND, ASSIGNOR TO UNITED SHOE MACHINERY CORPORATION, OF PATERSON, NEW JERSEY, A CORPORATION OF NEW JERSEY

DEVICE FOR USE IN COVERING HEELS

Application filed March 30, 1928, Serial No. 266,068, and in Great Britain May 17, 1927.

This invention relates to devices for use in covering unattached heels for boots and shoes with leather, fabric or other sheet material. It is shown herein as embodied in a jack for supporting a heel in convenient position for applying the cover thereto and for guiding the heel into the positions most favorable for the operator in conforming the cover to the surface of the heel.

10 In covering a heel, it is convenient to support it initially in an elevated position with its breast down and in this position the cover may be most easily wrapped about the rear curved surface of the heel and adjusted for a uniform margin of overlap. In conforming the covering material to the surface of the heel, it is the practice to work both ways from the rear median line of the heel. To facilitate this procedure, it is proposed to provide 20 heel sustaining means mounted for movement about a horizontal axis so that the heel may be swung downwardly on either side from its initial position, presenting its side faces successively in position where the operator may inspect and work upon them to the best advantage.

In accordance with an important feature of the invention, the supporting means for the heel is so constructed and arranged that, as the 30 heel is swung about a longitudinal axis in the manner indicated, it is also turned about a transverse axis and its rear curved face turned toward the operator, facing always in the same direction upon whichever side the heel may be swung. In a preferred construction for accomplishing this result, the heel supporting means is mounted for movement about two axes at right angles to each other and provision is made for constraining the 40 supporting means for bodily movement with the heel simultaneously about these two axes.

Preferably, and as herein shown, the heel supporting mechanism is so constructed and organized that the heel may be moved in the desired predetermined manner by the application of light pressure to the heel itself, a pressure which may be applied by the fingers of the operator in working the cover over the surface of the heel.

50 Other features of the invention relate to

means for holding the covering upon the heel to prevent slipping and to facilitate the operation of conforming the cover to the surface of the heel. These comprise two instrumentalities which are each useful singly but which are preferably employed together, thus presenting an additional and cooperative benefit. As herein shown, the first of these instrumentalities comprises a band constructed and arranged to be tensioned about the back of the heel after the cover has been presented thereto to prevent slipping of the latter and being connected to a lever by which it may be conveniently tensioned and locked. Preferably, an adjustable support is provided for sustaining the heel against the pull of the tension of the band.

The second instrumentality comprises means for gripping the margin of the covering at a point adjacent to the heel-seat edge of the heel, for the purpose of positively holding a part of the cover in the proper position while the remainder is conformed by the hands of the operator to the surfaces of the heel. In this connection, another feature of the invention consists in cover gripping members, disposed in separated or inoperative position while the heel is supported in its initial position but being movable automatically to engage the margin of the cover when the heel is moved in either direction from its initial position.

These and other features of the invention will be best understood and appreciated from the following description of a preferred embodiment thereof, selected for purposes of illustration and shown in the accompanying drawings, in which

Fig. 1 is a plan view of the device, with the parts in position for sustaining a heel 30 swung downwardly into its left-hand position; and

Fig. 2 is a view of the device in side elevation, showing the heel in its initial position.

The device comprises a base plate 2, having an upstanding integral collar 3 which forms a bearing for the vertically disposed stem 4 of a head 5. The head 5 is bored to form horizontal bearings for a stem 6 of a sec- 100

ond head or bracket member 7, having an upwardly extending arm 8 which is shaped at its extremity to engage the heel-seat surface of a heel and provided with prongs or 5 teeth for positively engaging the latter. Co-operating with the arm or jaw 8 and pivotally mounted upon a pin 9 extending between ears which form a part of the bracket member 7 is a lever 10, the upper end of 10 which is shaped to engage the tread face of the heel and provided with a prong or tooth for that purpose. The lower end of the lever 10 is formed to receive transverse trunnions 11 which project from a nut 12 threaded upon a horizontal bar 13, which is located at the axis of the bracket member 7 in a bore formed in the stem 6 for that purpose. The bar 13 extends entirely through 15 the stem 6 and is provided at its outer end with a hand wheel 14, by which the bar may be turned to shift the nut 12 and swing the lever 10 toward or away from the arm 8.

The bar 13 is mounted to rotate in the stem 6 when the hand wheel 14 is turned and it is also free for longitudinal movement toward the right, as viewed in Fig. 2, although it is constantly urged toward the left by a compression spring 17 seated in a recess in the stem 6 surrounding the bar 13, bearing 20 at one end against a shoulder in the stem and at the other against a shoulder on the bar 13 so as to urge the bar always toward the left, maintaining the end of the hub of the hand wheel 14 against the end of the 25 stem 6. The stem 6 is free to rotate in its horizontal bearing but is retained against longitudinal movement by a transverse pin 18, set in the head 5 and engaging a circumferential groove in the stem 6.

40 The hand wheel 14 may be turned to adjust the position of the movable jaw 10 to accommodate heels of varying height. It might also be used for swinging the jaw 10 for engaging or disengaging the heel but, 45 as a general thing, would be too slow for this purpose. In order to open the jaws rapidly and fully when it is desired to place a heel in position, treadle-operated means are provided for shifting the bar 13 longitudinally in opposition to the spring 17. To this end, a bell crank lever is pivotally mounted between lugs 21 upstanding upon the base plate 2. One arm 22 of the lever is connected to a treadle rod and the other arm 23 is provided with a face to engage the 50 end of the bar 13. A compression spring 24 normally holds the arm 22 of the bell crank lever elevated, its position being limited by a stop which engages a portion of the arm 23 on the left side of its axis of movement.

As already explained, the head 5 is mounted for movement about a vertical axis in bearings of the collar 3 and the bracket member 7 for movement about a horizontal axis

in the bearings of the head 5. These parts are interconnected in such a manner that these movements take place simultaneously or, in other words, when the bracket member 7 is moved about its horizontal axis, this axis is bodily shifted about the vertical axis of the head 5 so that a compound movement simultaneously about both axes is imparted to the heel supported by the bracket member 7. This result is secured by two intermeshing bevel gears, one gear 26 of 50 which is secured to the collar 3, the other gear 27 being secured to the stem 6. It will be apparent that when the bracket member 75 is swung in either direction, the action of the gears 26 and 27 will cause the stem 6 to turn with the head 5 in one direction or the other.

The initial position of the bracket 7 is determined by a spring-pressed plunger 30, mounted in the bracket member and having a pointed lower end for engaging a taper recess in the surface of the head 5. When the plunger 30 is so engaged, the bracket member 7 supports the heel above it in the elevated position shown in Fig. 2. In this position, the heel is held in the most convenient location for the initial application of the cover to its rear face by an operator facing the right-hand side of the device, as shown in Fig. 2.

Following such initial application of the cover, it is desirable to position the heel first with one side and then with the other side uppermost, as has been indicated. The heel 100 may be pushed downwardly on either side by the operator until it occupies some such position as shown in Fig. 1, further motion being limited by the engagement of the bracket member with one or the other of a pair of transversely extending lugs 32 upon the head 5. In this movement of the heel about the longitudinal horizontal axis of the bracket member 7, the heel is also turned about the transverse or vertical axis of the head 5 so that it is brought nearer the operator and disposed with its rear surface toward the operator. In Fig. 1, the heel is indicated in the position it would occupy if swung down upon the left-hand of the operator. If swung down upon the right-hand of the operator, it would occupy a symmetrically disposed position with its other side uppermost upon the other side of the device and with its rear curved surface still toward the operator.

The instrumentality for preventing any shifting of the cover upon the heel once it has been placed in contact with the rear surface thereof comprises a band or stirrup 33 of leather or similar material pivoted at both ends to a lever 34 which, in turn, is pivoted at 35 to the base of the arm 8 of the bracket member 7. The outer end of the lever 34 is provided with a broad face 36, by which

pressure may be applied to the lever to tension the band upon the heel.

Means for locking the lever in position comprises a ratchet segment 38 secured to and forming a part of the bracket member 7, and a spring pawl 37 arranged to engage the ratchet segment as the lever 34 is depressed.

Prior to the application of the cover, the lever 34 is swung upwardly and the stirrup 33 slipped forwardly out of the way of the heel-retaining jaws. This stirrup not only holds the cover against slipping upon the heel but prevents any tendency thereof to lift from the concave portion of the rear and the sides of the heel without covering sufficient surface to interfere with the further application of the cover.

In order to sustain the heel against the pull of the band 33 and prevent any tendency toward displacement in the heel-holding jaws, an adjustable support 45 is provided. This has a curved outer face for engaging the breast surface of the heel. It is pivotally mounted for a limited swinging adjustment and frictionally maintained in whatever position it may be set. The direction of pull of the band 33 is substantially across the pivot point of the support 45, so that there is no tendency to displace this member in operation.

The second instrumentality for retaining the cover in place comprises a stationary jaw 40 which is mounted upon the arm 8 of the bracket member and cooperates with a movable jaw 41, carried by a rod 42 mounted to move longitudinally in a bore formed in a boss 44 on the arm 8 and moved down or inwardly at all times by a compression spring 46 extending between the lower end of the boss 44 and the enlarged convex end of the rod 42. A cam surface 43, projecting from the head 5, is arranged to elevate the rod 42 and hold the cover gripping jaws open while the bracket member 7 occupies its initial position. This arrangement permits the application of the cover to the heel and the insertion of its margin adjacent to the rear edge of the heel-seat surface of the heel between the cover gripping jaws. As soon as the heel is swung out of its initial position, the end of the rod 42 passes off the cam surface 43 and the cover gripping jaws close positively, holding a portion of the cover in position upon the heel and preventing any shifting thereof toward the tread of the heel.

The operation of the device will be apparent from the foregoing description but may be briefly summarized as follows. Having made a preliminary adjustment of the heel gripping jaws to accommodate the type of heel to be covered, the operator depresses the treadle rod and presents a heel between the jaws or arms 8 and 10. When the treadle is released, the action of the spring 17 causes

the heel to be clamped in the position shown in Fig. 2. The cover is first applied and adjusted over the rear surface of the heel, the support 45 adjusted and the band 33 tensioned by depressing the lever 34. As the operator works the cover into conformity with the right-hand surface of the heel, he swings the heel downwardly toward the left, gradually bringing more and more of the right-hand surface uppermost and maintaining the rear surface of the heel toward him. When the conforming operation has proceeded to the breast edge of the heel, the heel is swung in the opposite direction through its initial position and down upon the right-hand side of the operator. The action of the cover gripping jaws takes place automatically as the heel is moved out of its initial position on either side. When the conforming operation has been completed, the pawl 37 is tripped to release the tension on the band 33 and the treadle rod depressed to separate the heel gripping jaws, so that the covered heel may be removed and a new heel substituted.

Having thus described my invention, what I claim as new and desire to secure by Letters Patent is:

1. A device of the class described comprising jaws relatively movable to engage a heel, and constrained for bodily movement with the heel simultaneously about two axes disposed at an angle to each other.
2. A device of the class described comprising jaws relatively movable to engage a heel, and constrained for bodily movement with the heel about vertical and horizontal axes simultaneously.
3. A device of the class described comprising jaws relatively movable to engage a heel by its tread and heel-seat surfaces, and constrained for bodily movement with the heel simultaneously about an axis substantially parallel to the longitudinal axis of the heel and an axis at right angles thereto.
4. A device of the class described comprising a swinging head with means for sustaining a heel therein, a support for the head movable about a different axis, and connections between said head and support whereby movement of either one produces movement of the other.
5. A device of the class described comprising a head movable about a horizontal axis and having means for sustaining a heel therein, a support for the head movable about a vertical axis, and geared connections between said head and support whereby the heel is constrained to movement in a path about said two axes simultaneously.
6. A device of the class described comprising a head arranged to swing about a horizontal axis, relatively movable heel-engaging jaws mounted thereon, a support for the head arranged to swing about a vertical

axis, and connections between said head and said support comprising a stationary gear disposed concentrically with respect to said vertical axis and an intermeshing gear disposed concentrically to the axis of the head.

5 7. A device of the class described comprising a head having means for sustaining a heel in elevated position with its breast down and being arranged to swing about a horizontal axis in either direction to position the heel with one or the other side down, and means constrained to move the heel as it is swung so as to maintain its rear surface facing always in one direction.

10 8. A device of the class described comprising a head having relatively movable heel-engaging jaws and being mounted for movement about an axis to support a heel retained by the jaws in different angular positions, and means located in said axis of movement for controlling the opening and closing of said jaws.

15 9. A device of the class described comprising jaws relatively movable to engage a heel and bodily movable with the heel into different positions, and operator-controlled means for separating said jaws to disengage the heel, operatively associated with the jaws in one position thereof and inoperative in all other positions of the jaws.

20 10. A device of the class described comprising a head mounted for movement about a fixed axis, jaws mounted thereon and relatively movable to engage a heel, and treadle-operated means for separating said jaws operatively associated therewith in one position of the head and inoperative in other positions of the head.

25 11. A device of the class described comprising a head mounted to swing about a vertical axis, jaws mounted thereon and relatively movable yieldingly to engage a heel, and treadle operated mechanism for opening the jaws located in operative relation to the jaws when the head occupies one position, said jaws being moved out of operative relation thereto when the head is moved to other angular positions about its axis.

30 12. A device of the class described comprising heel gripping jaws constructed and arranged to support a heel with its breast in a predetermined position, said jaws being mounted to move bodily with the heel when pressure is applied to the latter to swing it about a longitudinal axis and being constrained in such movement to rotate the heel also about a transverse axis so as to face its breast in the same direction upon whichever side the heel is moved.

35 13. A device of the class described comprising means for supporting a heel for bodily movement about a longitudinal axis to facilitate the application of a cover thereto, and means for yieldingly holding a cover against the rear and sides of the heel oper-

ative for releasing or engaging the cover in all positions of the supporting means.

40 14. A device of the class described comprising a head movable about two axes disposed at an angle to each other, heel gripping jaws carried by said head and arranged to support a heel to be covered, and cover retaining means mounted on the head and operative in all positions thereof.

45 15. A device of the class described comprising means for supporting a heel to be covered with its breast disposed in a predetermined direction, and means for gripping the margin of the covering at a point adjacent to the heel-seat edge of the heel.

50 16. A device of the class described comprising movable means for supporting a heel to be covered with its rear curved surface uppermost, and cover gripping means disposed adjacent to the rear end of the heel-seat edge of the heel and movable with the heel upon its support.

55 17. A device of the class described comprising a pivotally mounted head having means for supporting a heel to be covered, and a co-operating cover gripping device inoperative in the initial position of the head and movable to engage the margin of the cover when the head is moved.

60 18. A device of the class described comprising a pivotally mounted head having means for supporting a heel to be covered, relatively movable cover grippers carried by the head, means for maintaining said grippers open while the head occupies its initial position, and means for closing the grippers when the head is moved out of its initial position.

65 19. A device of the class described comprising a head having jaws for engaging the tread and heel-seat surfaces of a heel, a cover holding band constructed and arranged to be tensioned about the back of the heel, and means for engaging the breast face of the heel to support the heel against the pull of said band.

70 20. A device of the class described comprising a head mounted to swing about a horizontal axis and having jaws for supporting a heel with its breast down in position above the head, an adjustable support shaped to bear against the breast face of the heel, a cover holding band, a connected lever for tensioning the band and locking it under tension, and cover gripping jaws constructed and arranged to close automatically upon the margin of the cover when the head is moved to swing the heel in either direction from its initial position.

75 21. A device of the class described comprising a head, opposed heel sustaining jaws mounted thereon, means for effecting a slow positive adjustment of one of said jaws while retaining it in opposed relation to the other jaw, an operator-controlled member movable in one direction to cooperate with said means

for quickly moving the first-mentioned jaw away from the other jaw, yielding means arranged to resist said movement of separation, and separate yielding means for moving said member in the opposite direction.

5 In testimony whereof I have signed my name to this specification.
